UNITED STATES PATENT OFFICE.

JOHN HENRY PICK, OF STAMFORD, ENGLAND, ASSIGNOR TO THE PICK MOTOR COMPANY, LIMITED, OF STAMFORD, LINCOLN, ENGLAND.

BRAKE.

SPECIFICATION forming part of Letters Patent No. 744,792, dated November 24, 1903.

Application filed February 7, 1903. Serial No. 142,264. (No model.)

To all whom it may concern:

Be it known that I, JOHN HENRY PICK, a subject of the King of Great Britain, residing at Blackfriars Works, Blackfriars street, 5 Stamford, Lincoln, England, have invented new and useful Improvements in Brakes, of which the following is a specification.

This invention relates to an improved brake especially applicable for use in connection 10 with motor-vehicles, but also applicable for other purposes.

According to my invention I fix a drum upon a moving axle or shaft, and in connection with this drum I use a metal band, preferably lined with leather or other material 15 and having at its two ends boxes through which a shaft, carried in a fixed standard or support, extends. This shaft has formed upon or attached to it a cam, which works in 20 the boxes of the brake-band and which is so arranged that the partial rotation of the said cam causes the boxes to move in opposite directions, and thereby grip the band on the drum. The spring of the band is sufficient 25 to remove the brake from frictional contact with the drum.

The brake is preferably operated by a lever mounted upon the cam-shaft.

In the accompanying drawings, Figure 1 is 30 a side elevation of a brake made according to the invention. Fig. 2 is an end elevation thereof, and Fig. 3 is a sectional elevation of the band-boxes and cam.

a is the moving axle or shaft which is to be 35 braked, and *b* is the drum which is keyed thereto, the said drum being provided with a peripheral groove *b'*.

c is the metal band, which, as above described, is advantageously provided with the 40 leather or other suitable lining *d* and which is coiled around the peripheral groove *b'* in the drum *b*.

e and *f* are the two boxes to which the two

ends of the band *c* are secured, the said boxes being formed with guiding-apertures *e'* and *f'*, 45 respectively, through which passes the concentric portion of the shaft *g* rotatably mounted in the standard or support *h*, which is here shown carried by a sleeve *i* on the shaft *a*.

j is the cam, which is keyed upon the shaft *g* inside the two boxes *e* and *f*. This cam is shown of an elliptical shape, the ends of the boxes against which the said cam bears being of a corresponding shape, as will be seen from Fig. 3. When the cam is in the normal position—that is to say, in the position shown in the drawings with its major axis upright—the band *c* is slack upon the drum *b*. If, however, the shaft *g* be turned in either direction through the medium of the lever *k*, keyed 55 upon it, the two boxes are moved by the cam in opposite directions or toward one another, thereby tightening the band *c* upon the drum *b*. Upon releasing the lever *k* the spring or elasticity of the band *c* is sufficient to take it 60 out of frictional contact with the drum. 65

Having now particularly described and ascertained the nature of my said invention and in what manner the same is to be performed, I declare that what I claim is—

In a brake, the combination with a drum and a metal band surrounding the same, of a box attached to each end of said band, the said boxes having each a guiding-aperture, a shaft having a concentric portion passing 75 through said guiding-apertures and a cam on said shaft adapted to bear against the ends of the boxes to move them in opposite directions and tighten the band upon the drum, whereby the said band grips the drum throughout its 80 entire circumference with substantially equal pressure, substantially as described.

JOHN HENRY PICK.
